5 Claims. (Cl. 120—19)

My invention relates to lead pencils in which the leads are renewable, advanced as used, and retractable when not in use.

The principal objective of my invention is to provide a pencil in which the leads are renewable, and wherein the advancement of the lead is visible and controllable.

I am aware that there are many pencils on the market in which the leads are renewable. In these pencils the lead is confined though not supported in an enlarged elongated cylindrical shell out of which the lead is dropped through jaws by the force of gravity. The usual procedure employed to advance the lead is to unclamp the jaws and then clamp them when enough lead has passed through them. The closing of said jaws becomes a matter of dexterity.

In drafting rooms the leads used may range from F or softer to 8H in hardness. The harder the lead the stronger it is. It follows that it is not expedient to expose as much soft lead as hard lead. Experience soon teaches the best length of lead to expose in order to minimize breakage. This length I seek to control.

In my improved pencil I have complete control of the lead exposure which is always visible.

The preferred form of my pencil together with some of the possible variations of its parts is illustrated in the accompanying drawings of which:

FIG. 1 is a side elevation of a regular pencil.

FIG. 2 is a top view of the same pencil.

FIG. 3 is an elevation of a lead-carrying member and the adjusting cap.

FIG. 4 is an elevation of the casing and its head cap.

FIG. 5 is a greatly enlarged vertical section on the line 5—5 of FIG. 1.

FIG. 6 is a similar section on the line 6—6 of FIG. 1.

FIG. 7 is a similar section on the line 7—7 of FIG. 1.

FIG. 8 is a similar section on the line 8—8 of FIG. 1.

FIG. 9 is a partial longitudinal section on the line 9—9 of FIG. 2.

FIG. 10 is a similar section to which has been added an eraser.

FIG. 11 is a partial elevation showing a clip attached to the casing.

FIG. 12 is a partial longitudinal elevation showing the use of a plastic head cap.

FIG. 13 is a similar elevation showing the said head cap as being a frusto conical wire spring.

Throughout the drawings and the specification similar numerals refer to similar parts.

The pencil P includes two elongated lead-confining members 1 and 2 semi-circular in cross section as shown in FIG. 7. These members 1 and 2 may be formed of wood, plastic, or other suitable material. The flat face 3 of each member 1 and 2 is provided with a semi-circular groove 4 adapted for a running fit of the lead diameter being used. This groove 4 extends the length of the members 1 and 2 which are separated by the intervening spacer 5 positioned and secured at one end of said members to provide a two-part oval structure 6 as viewed in FIG. 5. The forward end of the members 1 and 2 are formed with a long taper 7 as shown in FIGS. 1 and 3.

The members 1 and 2 are enclosed in a casing C oval in interior cross section and preferably circular in exterior cross section to facilitate installing end caps. This casing C is formed of any suitable material that is clear or through which the contents may be seen, for instance, one

2

of the many plastics through which contents are viewable. The oval interior of the casing C is slightly larger than the oval cross section of the combined lead-carrying members 1 and 2. The reason will soon be apparent.

5 The casing C is provided with a head cap 8 or 8' and the combined lead-carrying members 1 and 2 are fitted with an adjusting cap 9 or 9'. This latter cap may be formed of plastic or metal and/or extended to embrace an eraser 10 as shown in FIG. 10. I prefer to make the head cap 8 of a plastic which can yield slightly under pressure. FIG. 12 illustrates this form of cap 8, while FIG. 13 shows the cap 8' consisting of a conical spring which yields slightly when a tapered member is forced into it thus tending to grip said member. The opening 11 or 11' in the small end of the tapered head cap 8 or 8' is oval in cross section.

Between the adjusting cap 9 or 9' and the adjacent end of the casing C and movable endwise over the combined members 1 and 2 is the cylindrical slide 12 which carries the spline 13 positioned in and movable longitudinally in the space 14 provided between the two members 1 and 2. See FIG. 2.

20 The head cap 8 or 8' is provided with a tapered oval bore 15 or 15' adapted to receive the tapered ends 7 of the members 1 and 2 to cause the members 1 and 2 to be moved toward each other to clamp between them any lead L positioned in the groove 4. It is apparent that the spline 13 may be moved by the slide 12 into contact with the end of any lead L in the groove 4 and said lead moved 25 forward in the groove 4 any desired distance.

25 Into the members 1 and 2 rearward of the tapered portion 7 thereof I press into each oppositely disposed means, as small ball bearings 16, which project from said members 1 and 2 sufficiently to engage the short diameter 30 of the oval interior of the casing C but not the long diameter thereof.

30 As a consequence it will be apparent that if the members 1 and 2 are rotated in either direction by the adjusting cap 9 or 9' the ball bearings 16 will eventually engage the interior surface of the casing C and thus force the members 1 and 2 together to clamp the lead L between them.

35 In my pencil the lead L is not only supported throughout its length but clamping pressure is applicable over most of its length.

40 The pencil P is loaded with a length of lead L which is inserted through the bore 15 in the head cap 8 or the bore 15' in the head cap 8' into the groove 4 in the members 1 and 2.

45 To eject a desired length of lead for use, the casing C is moved to the left, we will say, over the members 1 and 2 until the tapered end 7 of said members is clear of the head cap 8 or 8' and within the casing. The slide 12 is then moved to the left over the members 1 and 2 until the spline 13 comes into contact with the lead L in the groove 4 whereupon the slide 12 and its spline 13 is moved still farther to the left until the desired length of the lead L is exposed beyond the tapered ends 7 of the members 1 and 2.

50 When the desired length of the lead L is exposed the adjusting cap 9, and incidentally the members 1 and 2 to which it is secured, is moved to the left until the exposed lead L is positioned beyond the tapered end of the members 1 and 2 as shown in FIG. 2 whereupon the lead L is 55 clamped between said members by turning the adjusting cap 9 or 9' in either direction about an eighth of a revolution. An eighth of a turn in the opposite direction frees the lead from clamping pressure.

55 Since my pencil admits of many changes in design I do not limit my invention to the exact design shown and described but extend it to all that comes fairly within the scope of the appended claims.

What I claim as new over the prior art follows:

1. A pencil having in combination an elongated transparent hollow casing having an interior oval cross section; a head cap joined to one end of said casing and having a tapered bore therethrough of oval cross section; a lead; a lead confining unit manually retractable within the casing having a tapered end portion adapted to engage the tapered bore of the head cap and project therethrough, said unit including a pair of spaced apart elongated members semi-circular in cross section arranged with their flat faces adjacent to each other said flat faces being provided with oppositely disposed semi-circular grooves in which the lead is slideable endwise; means positioned at one end and between the flat faces of the lead-confining members to hold them in spaced apart relation to provide the unit with an oval cross section; a slide having a spline moveable between the spaced apart members of the unit and adapted to engage lead within the unit; and means adjacent the open end of the unit and projecting outwardly therefrom to provide said end of said unit with an outside diameter greater than the shorter inside diameter of the casing oval interior and lesser than the longer diameter thereof whereby said unit is freely shiftable in said casing when said means extends along said longer diameter but is frictionally gripped in said casing when rotated

15
20
25

therein to move said means from along the longer diameter toward said lesser diameter.

2. The structure of claim 1 in which the casing exterior is circular in cross section.
3. The structure of claim 1 in which the head cap is formed of yieldable plastic.
4. The structure of claim 1 in which the head cap is of wire wound as a frusto conical section.
5. The structure of claim 1 in which the last-named means consists of oppositely disposed ball bearings pressed into the unit members.
